UNITED STATES PATENT OFFICE.

ALFRED NATHAN, OF LEIPZIG, GERMANY.

PROCESS OF TREATING CHEAP SKINS IN IMITATION OF MORE EXPENSIVE FURS.

Application filed April 13, 1926, Serial No. 101,808, and in Germany June 24, 1925.

The object of this invention is to treat skins for ornamental purposes, and more particularly to provide cheap skins with markings in imitation of more expensive furs, so that a cheap and durable substitute for such furs is obtained.

In the accompanying drawing,—

Figure 1 is a plan view of a short haired skin, such as a calf skin treated in accordance with my invention.

Figure 2 is a face view of the die or embossing plate.

Figure 3 is a sectional view taken on line 3—3 of Figure 2.

I select for the purposes of the invention a unicolored short-haired or smooth-haired skin A, for example calf-skin. By smooth-haired skin I mean a skin on which the hairs lie flat. This skin may be dressed and generally prepared according to well known methods, and may be dyed if dyeing is suitable for the particular purpose in view. According to the invention I stamp or emboss the unicolored skin as indicated by the deep-shaded markings (one indicated at A') on the unicolored skin surface in Figure 1, with a die plate or plates B having the desired pattern B'. The pattern may, as already stated, be a pattern in accordance with that of some more expensive skin which lends itself to reproduction in this way, for example foal or "Breitschwanz" (broad-tail) but alternatively it may be an arbitrary pattern, regular or otherwise. The plate may be heated, the temperature and duration of the pressure being such as are found to give good results in each particular case; a definite general rule cannot be given in regard to the same, because not only do the skins of different species differ greatly from each other in their texture and so on, but individual skins of the same species vary considerably.

The plate may be inked to impart a coloured pattern. The colouring of the pattern may improve its effect, and may in some cases be necessary as an adjunct to perfect imitation, but the stamping or embossing action affects the skin in respect of the directions in which the hairs lie, so that apart from the application of colouring matter by the plate the effect of a coloured pattern is to

some extent obtained, due to the different reflections of light by the embossed skin. By this means alone natural markings which are due to "partings" of the hairs and so on may be closely imitated, but as already stated the effects thus obtained may be increased by applying colours. Moreover, the application of colour may, by impregnating the skin, assist in retaining the hairs in the positions imparted to them by the embossing or stamping, and the pattern is thus rendered more durable.

As regards the general colouring of the skin, the desired effect is, or may be, obtained in part by suitable selection of the raw skin and in part by dyeing the skin, or by inking the whole of the plate used for embossing, as when a skin of a single colour, for example a "Breitschwanz" (broad tail) skin is to be imitated.

I am aware that imitations of skins have been produced by embossing plush and other fabrics, the same being generally ironed, brushed or steamed and then treated with hot embossing plates. The imitation is in that case, of course, purely superficial, because the material itself is not a skin. With my invention, on the other hand, the material is in fact a skin, and is accordingly capable of being used, in all or most respects, as an actual substitute for the skin of which it is an imitation.

Having now particularly described and ascertained the nature of my said invention and in what manner the same is to be performed, I declare that what I claim is:—

The process of treating a natural fur to impart to it an appearance of a different natural fur, which consists in taking a unicolored natural skin having short or smooth hairs upon its haired side and embossing the said haired side of said skin with markings of a pattern and coloring corresponding to the natural fur to be imitated while physically displacing hairs at points from their natural positions so as to produce hair "partings" with color shades giving different light reflexes.

In testimony whereof I have hereunto affixed my signature.

ALFRED NATHAN.
